METERING MOTOR OPERATED PUMP FOR
DISPENSING BEVERAGES

Bruce G. Copping, Atlanta, Ga., and Evert S. Wegman, East Longmeadow, Mass., assignors to Westinghouse Electric Corporation, East Pittsburgh, Pa., a corporation of Pennsylvania

Application February 10, 1945, Serial No. 577,204

4 Claims. (Cl. 225—26)

1

This invention relates to beverage dispensing apparatus and particularly to apparatus of the type wherein proportioned parts of cold syrup and cold carbonated water are dispensed into a cup or other receptacle in which the beverage components are mixed.

The invention is particularly applicable to such apparatus wherein the amount of syrup dispensed is proportioned accurately in response to the flow of the water by means of a metering device which regulates the syrup flow quantitatively in response to pressure applied in common to the metering device and the carbonated water container.

In such apparatus, the syrup is pumped from its receptacle and discharged to the cup by pressure applied from a regulated source, such as the carbon dioxide cylinder used in charging the carbonated water, which pressure is also applied to the carbonator. The carbonator and its container water are maintained at a cold dispensing temperature and likewise the syrup is maintained at the same temperature. However, the viscosity of the syrup and water, not being the same, variations in temperature, even though they be the same for both the syrup and water, will affect the proportions of syrup and water in the dispensed beverage unless some means is provided to compensate for the varying viscosities.

In the system here described, this is accomplished by providing a metering device comprising a closed hydraulic system containing water which is forced from one end of that system to the other through a controlled orifice in response to carbon dioxide pressure to actuate a syrup pump. The carbonated water is discharged from its container to the cup through a nozzle having rate of flow characteristics similar to that of the controlled orifice in the hydraulic system and the pressure applied to the carbonated water is the same as that applied to the closed hydraulic system. As both fluids being displaced, that is, the water in the closed system, and the carbonated water are the same and have the same viscosity at the same temperature, and as both orifices are hydraulically similar, it follows that the discharge of syrup from the syrup pump actuated by the hydraulic system will be accurately proportioned to the discharge of water from the carbonator. Regulation of the quantity of syrup discharged for a given amount of carbonated water can be had by making the orifice in the hydraulic system adjustable, this being desirable to vary the concentration of the beverage.

In a system as here described, it has been pro-

2

posed to make the syrup pump and metering device as a unit and to immerse them in the syrup tank. Operatively this makes a satisfactory arrangement, but has the disadvantage that the metering device is not readily accessible for adjustment.

An object of the invention, therefore, is to so dispose the metering device with respect to the rest of the apparatus that it may be readily serviced and adjusted.

A further object is to so dispose the metering device that it is outside the syrup tank, for sanitary reasons, and is disposed in a water bath whose temperature is that of the carbonated

15 water to be dispensed.

Another object is to provide an arrangement of the syrup pump and metering device such that both those parts can be removed from the rest of the apparatus without breaking the hydraulic

20 system, or in which either of those parts can be removed separately.

These and other objects are effected by the invention as will be apparent from the following description and claims taken in connection with

25 the accompanying drawings, forming a part of this application, in which:

Fig. 1 is a diagrammatic elevation, partly in section, showing an assembly comprising the invention;

30 Fig. 2 is a vertical section, on an enlarged scale, showing a syrup pump;

Fig. 3 is a vertical section on an enlarged scale showing a metering device; and

Fig. 4 is a vertical section through a check

35 valve provided in the syrup line between the pump and the cup.

Referring to Fig. 1, the dispensing apparatus comprises an insulated tank 10 for storing a quantity of water. The water is derived from

40 any suitable source, such as a city water main, and its level is maintained at a selected height by a suitable level control device (not shown).

The water is refrigerated by a refrigerant coil 11 connected by conduits 12 and 13 to a suitable re-

frigerant condensing unit (not shown) which is

45 in turn controlled by a temperature-responsive device immersed in the water. Uniformity of water temperature is insured by a motor driven agitator 14 which circulates the water into con-

50 tact with the refrigerating coil 11. This water, when carbonated, forms a component of the beverage to be dispensed.

A syrup tank 15 is immersed in the water bath and its contents are cooled by the water bath.

55 A carbonator 16 is also immersed in the water

bath and cooled thereby. The carbonator is supplied with water intermittently through a conduit 17 which leads from a pump (not shown). The pump draws its water from that stored in tank 10. Carbon dioxide is supplied to the carbonator from a cylinder 18 through a pressure-reducing valve 19 and conduit 20. Carbonated water is discharged from the carbonator under pressure through a valved dispensing nozzle 21 of selected hydraulic flow characteristics. The valve (not shown), which lies inside the nozzle body, is controlled by a solenoid 22 through a pivoted lever 23. The receptacle for the dispensed beverage is here shown as a cup 24.

The syrup dispensing system comprises a pump 25 immersed in the syrup tank, a metering device 26 immersed in the water tank and a conduit 27 leading from the syrup pump to the cup. The pump and metering device are shown in detail in Figs. 2 and 3, respectively, as explanatory of, but not per se part of, this invention.

Referring to Fig. 2, a suitable fitting 28 is disposed in the bottom of the syrup tank for detachably receiving the main body 29 of the pump, a detachable coupling being indicated at 30. The pump comprises a flexible diaphragm 31 movable in a chamber 32 and normally held in its uppermost position by a spring 33 and the head of syrup in the tank. The pump chamber 34 communicates with the syrup tank through a spring-seated check valve 35 and syrup is discharged from the pump to conduit 27 through chamber 36 provided in the fitting 28. The conduit 27 is provided with a spring-seated check valve 37 (Fig. 4) between the pump and the cup. Thus on the suction stroke the pump draws syrup from the tank into chamber 34 past check valve 35, the valve 37 being seated, while on the discharge stroke (shown in Fig. 2) valve 35 seats and syrup is discharged from the chamber 34 through chamber 36 and conduit 27 past check valve 37 to the cup 24.

The metering device (Fig. 3), through which the pumping stroke is controlled, comprises a hollow body 40 connected by a detachable coupling 41 to the bottom of the water tank 10. A flexible compressible sac 42 is tightly sealed at its open end against a passaged body 43 which is, in turn, sealed in fluid-tight engagement with the open end of hollow body 40. Thus the interior of the sac 42 is sealed from its exterior in fluidtight relationship. The space 44 between the exterior of the sac 42 and the inner wall of hollow body 40 provides a chamber into which carbon dioxide is discharged under pressure to squeeze the sac when a drink is to be dispensed. Carbon dioxide is supplied to chamber 44 at that time from cylinder 18, past regulating valve 19, solenoid valve 45, conduit 46 and conduit 47 to passage 48 provided in body 43 and thence to the chamber.

The solenoid valve 45 is normally closed and is opened in timed relation with the solenoid 22 controlling the flow of carbonated water to the cup only when a drink is to be dispensed. The valve 45 is preferably of the well-known "two-way" type which provides a passage from the CO₂ source to the conduits 46, 47 and chamber 44 when the solenoid is energized and connects the chamber 44 to the atmosphere to release the accumulated CO₂ when the solenoid is deenergized. It should be noted that conduits 46 and 47 are connected by a detachable coupling 49.

The energy of the carbon dioxide is applied to the syrup pump from the metering device through 75 and pump be detachably connected in their re-

a closed hydraulic system comprising the sac 42, adjustable orifice means 50, chamber 51 and passage 52 formed in body 43, flexible conduit 53 and conduit 54 to a closed chamber 55 formed above the pump diaphragm 31 by the pump body 28 and cap 56. This closed hydraulic system is filled with a liquid, water in this case, which operates as a liquid piston to move the pump diaphragm downwardly (Fig. 2) when CO₂ pressure is applied to the exterior of sac 42.

The control of the rate of water flow from the interior of sac 42 to the pump diaphragm 31 is had through an adjustable metering element comprising a tapered orifice 57 provided in a plate 58 covering the open end of sac 42 and a similarly tapered adjustable plug 59 extending into but not closing the orifice. The plug 59 is provided with a head 60 which may be grasped through the flexible sac 42 for adjustment and also carries a stem 61 extending upwardly through the body 43 and provided externally with a lock nut 62 which maintains the adjustment of the plug. The passage of fluid from the sac 42 to chamber 51, passage 52 and conduits 53 and 54 to the pump diaphragm chamber 55 is through orifice 63 centrally of plug 59 and transverse passages 64 to the passage 65 formed between the tapered portions of plug 59 and orifice 57 and thence to the chamber 51.

30 A check valve 58a of known construction is provided in the separator plate 58 to permit quick return of the water from the pump side of the hydraulic system when pressure on the pump diaphragm is relieved through valve 45 when its solenoid is deenergized. When the pressure is so relieved at the end of the pumping stroke, spring 33 restores diaphragm 31 to its unstressed position and syrup is drawn into the pump from the tank through check valve 35, ready for the next pumping operation.

40 The adjustable metering element here shown is but a diagrammatic representation of a passage capable of affording liquid flow of the required hydraulic characteristics between the sac 42 and the pump diaphragm 31. It is sufficient to say for the purposes of this application that the rate of flow through this element is proportioned to the rate of carbonated water flow through nozzle 21, so that syrup and water are always dispensed in constant proportions and in constant quantities as determined by the adjustment of the metering element.

45 It is necessary that the metering element be adjustable both for initial installation and to take care of varying quantities of syrup as required in the mixed beverage. It is also desirable that both the syrup pump and the metering device be readily removable from the apparatus for cleaning and repair. It is further desirable that 50 the metering element be disposed outside the syrup tank and yet be capable of adjustment without disturbing its hydraulic connections with the pump. It is also necessary that the metering device be maintained at the temperature of the beverage being dispensed so as not to disturb the flow characteristics of the hydraulic system by a change in its viscosity with relation to the viscosity of the carbonated water flowing through the dispensing nozzle.

55 We have, therefore, provided (1) that the metering device be separated from but hydraulically connected to the pump, (2) that the metering device be disposed in the water tank outside the syrup tank, (3) that the metering device 60 and pump be detachably connected in their re-

spective tanks, (4) that the connections between the metering device and the pump be such that the device can be removed from its tank without disturbing its hydraulic connections with the pump, and (5) that the pump and metering device can be removed from their respective tanks without disturbing their hydraulic connections.

To these ends, reference is made to the detachable couplings 30 for the pump with its tank and 41 for the metering device with its tank. It will also be noted that the conduit 53 leading from the metering device to the pump is flexible, for example, a heavy rubber tube or a plastic tube. This tube passes through a slot 66 provided in the neck of the syrup can, the rubber grommet 67 which seals the slot being either split or removable with the tube. The tube or conduit 53 is preferably detachably coupled, as at 68, to the conduit 54 leading to diaphragm chamber 55.

With the foregoing arrangement, the metering device can be adjusted by separating the coupling 49 in the carbon dioxide line, separating the device from the tank 10 at its detachable coupling 41 and removing the device from the tank by virtue of the flexible tubing 53 without disturbing the hydraulic connections with the pump. If it is also desired to remove the pump, it can then be uncoupled from its tank at 30 and the connected metering device and pump removed from the apparatus by reason of the slot 66 in the neck of the syrup can. The conduit 54 may be either flexible or rigid, as circumstances require. The same is true of the carbon dioxide conduit 47.

While the invention has been shown in but one form, it will be obvious to those skilled in the art that it is not so limited, but is susceptible of various changes and modifications without departing from the spirit thereof.

What is claimed is:

1. Beverage dispensing apparatus comprising, a tank for containing water to be dispensed, a syrup tank, a syrup pump associated with and operatively connected to the syrup tank, an adjustable metering device for operating the syrup pump detachably connected in and near the bottom of the water tank, and a connection adapted to contain liquid joining the metering device and the syrup pump, said connection being so constructed and arranged that the metering device may be removed from the water tank for adjustment without breaking said connection.

2. Beverage dispensing apparatus comprising, a tank for containing water to be dispensed, a syrup tank, a syrup pump associated with and operatively connected to the syrup tank, an adjustable metering device for operating the syrup pump detachably connected in and near the bottom of the water tank, a connection adapted to contain liquid joining the metering device and the syrup pump and extending over a side wall of the syrup tank, said connection being so constructed and arranged that the metering device may be removed from the water tank for adjustment without breaking said connection.

3. Beverage dispensing apparatus comprising, a tank for containing water to be dispensed, a syrup tank, a syrup pump detachably associated with and operatively connected to the syrup tank, a metering device for operating the syrup pump detachably connected in and near the bottom of the water tank, and a flexible conduit adapted to contain liquid connecting the metering device with the syrup pump whereby the metering device may be removed from the water tank without disconnecting the flexible conduit.

4. Beverage dispensing apparatus comprising, a tank for containing water to be dispensed, a syrup tank, a syrup pump detachably associated with and operatively connected to the syrup tank, a metering device for operating the syrup pump, said metering device being disposed in and detachably connected near the bottom of the water tank, and a flexible conduit adapted to contain liquid connecting the metering device with the syrup pump, said metering device, pump and conduit being so constructed and arranged that the assembled unit may be removed from the apparatus without breaking the conduit joining the pump and metering device.
